LOCOMOTIVE VALVE MECHANISM

Orville Z. Frazier, River Rouge, Mich., assignor of one-third to Cassell A. Mott, one-eighth to Oscar C. Haynes, and one twenty-fourth to Bernard W. Streets, all of South Bend, Ind.

Application January 20, 1932, Serial No. 587,698

4 Claims. (Cl. 121—162)

This invention relates to power reverse gears, and particularly to reverse gears for controlling the valve action of locomotive steam engines.

The object of the invention is to provide a simple and reliable reverse gear which may be operated (preferably under steam power) from the cab of a locomotive, and which will effect an automatic cut-off of the power in case the engineer fails to complete a manual control operation.

The above and various other objects the invention attains by the construction hereinafter described and illustrated in the accompanying drawings, wherein:

Fig. 1 is a view in side elevation of a locomotive, equipped in accordance with the invention.

Fig. 2 is a fragmentary elevational view of the other side of said locomotive, particularly disclosing the engine valve gearing.

Fig. 3 is a cross sectional view of said locomotive, taken upon the line 3—3 of Fig. 1.

Fig. 4 is an elevational view (partially in section) of a lever mechanism adapted to operate the throttle in common with a pair of valves controlling delivery of an energizing fluid to the reversing gear.

In these views, the reference characters 1 and 2 respectively designate the barrel and cab of a locomotive, the drive wheels 3 of which are driven through the usual side connecting rods 4 and main connecting rods 5, the latter extending from the usual cross heads 6 reciprocating in guides 7. As is general practice, a steam engine 8 is mounted at each side of the front end of the locomotive, each actuating a cross head 6 through a piston rod 10. A steam delivery pipe 17 is connected with each engine through branches 18, and the admission and exhaust of steam is controlled by a sleeve valve or the like (not shown), driven by a stem 12 rearwardly projecting from each engine.

The stem 12 is connected to and actuatable by an upright lever 23, commonly known as the combination lever. This lever comprises an arm 45 downwardly projecting from said stem and linked as indicated at 22 to the cross head of the corresponding engine, and a relatively short arm upwardly projecting from said stem and linked as shown at 25 to a pin 26, adjustable in an arcuate slot formed in an oscillatory lever 27, commonly termed in this art the reverse link. The reverse link at each side of the locomotive is adapted to be rocked (through mechanism not shown) by the cross head 6 at the other side of the engine, said mechanism including a link 33

engaging said cross head by means of link 24.

Each pin 26 is adjustable in the arcuate slot of its reverse link 27 to regulate the throw of said pin and to position said pin either above or below the rocking axis of the link, whereby the direction of drive of the locomotive may be reversed. To effect such an adjustment, a link 34 intermediate engaging each link 25 is upwardly extended to engage a forwardly projecting arm 35 of a bell crank, one of which is pivoted at each side of the locomotive. Said bell cranks are further each formed with an arm 36, projecting upwardly on one thereof and downwardly on the other. Rearwardly extending links 38 connect the bell crank arms 36 to the lower ends of a pair of arms 39 rigidly carried by a rock shaft 40, mounted transversely of the locomotive. At one side of the latter, said shaft further rigidly carries a worm wheel segment 41 adapted to be driven by a worm wheel 42 fast upon a shaft 43 extending lengthwise of the locomotive. Said shaft may be alternatively driven in reverse directions by either of two small rotary motors 44 associated with the respective ends of said shaft. Pipes 45 for delivering steam or some other energizing fluid to said motors extend to the locomotive cab, being there individually controlled by valves 46. The valve members of the latter are normally seated by springs 47, and the stems 48 of said valves are selectively engageable by an articulated lever 49, 50 for alternatively admitting steam to the pipes 45. In opening either valve 46, the handle member 49 of said lever rocks about a hinged connection 51 between the sections 49 and 50.

Said lever is further adapted to rock, as a whole, about a pivot 52 transverse to the hinge axis 51, for the purpose of actuating a pull rod 53 exercising control of the usual throttle valve (not shown).

The drive from each motor 44 to the shaft 43 is through a clutch 54 adapted to be opened and closed by a rocking lever 55. A rod 56 slidable in brackets 57 mounts a pair of coiled springs 58 acting on the levers 55 to normally hold the companion members of each clutch in driving engagement. An arm 59 rigidly rising from the shaft 40 has a pin and slot engagement with the slide rod 56, whereby said rod reciprocates in unison with the rocking travel of said arm. Said rod is formed with a pair of shoulders 60, which upon a predetermined rocking travel of the arm 59 in either direction are engageable with one or the other of the levers 55 to open the corresponding clutch 54. Thus upon a predetermined limiting

actuation of the described reverse mechanism by either motor 44, the drive from the latter is automatically cut off. Thus the mechanism is safeguarded against damage through possible neglect of the engineer to deenergize either motor 44 upon a limiting actuation of the described parts.

To afford a definite indication, in the locomotive cab, of the effective position of the reverse gear, a pointer 61 is mounted in the cab to travel 10 with reference to an arcuate dial 62, bearing suitable indicia, said pointer being actuatable from the upper end of the arm 59 through a Bowden wire 63.

In operation of the described reverse gear, the 15 cross head of each engine, in its reciprocation, acts through the corresponding link 33 to rock the reverse link 27 at the other side of the locomotive, and said reverse link, acting through the corresponding link 25, serves to primarily actuate the combination lever 23 actuating the valve 20 mechanism of the other engine. Each combination lever is driven, to a much lesser degree, from the cross head of the corresponding engine, whereby the proper lap and lead are imparted to the 25 valve action.

By swinging the handle section of the lever 49, 30 50, transversely, the engineer can admit steam (or some other energizing fluid) selectively to the motors 44 and thus drive the shaft 43 in either direction. This permits the pin 26 to be 35 raised or lowered in the slot of the reverse link 27, so as to regulate the stroke of the stem 12 and consequent uncovering of the intake and exhaust ports (not shown), and so as to establish said pin 35 selectively above or below the rocking axis of the reverse link.

Ordinarily, after an energization of the reverse 40 mechanism, the engineer will cut off steam from the motor 44 employed in such energization. In case the engineer fails to exercise such control, one or the other of the clutches 54 will be automatically released as the pin 26 reaches a limiting position, any damage to the mechanism being thus prevented.

The described indicator keeps the engineer conveniently informed as to the effective position of the pin 26, and the locomotive control is simplified by using a single lever 49, 50 to control both the throttle and the reverse mechanism. 5

What I claim is:

1. A reversing mechanism comprising a shaft, a pair of drive motors reversely effective upon opposite ends of said shaft, means for selectively energizing said motors, a clutch connection from 10 each motor to said shaft, means yieldably acting on each clutch connection tending to close such connection, a pivoted lever, a speed reducing drive connection from said shaft to said lever, a rod slidably actuatable by said lever in substantial 15 parallelism with said shaft, and elements actuatable by said rod in its respective limiting positions of travel each effective upon one of said clutch connections to open the same.

2. A reversing mechanism as set forth in claim 20 1, each of said elements being a lever pivoted between its ends, one of said ends engaging one of said clutch connections, and the slide rod having a shoulder adapted for actuating engagement with the other of said ends.

3. A reversing mechanism as set forth in claim 25 1, said speed-reducing drive connection comprising a worm-wheel element connected to said lever, and a worm on said shaft, having driving engagement with the worm-wheel element.

4. A reversing mechanism comprising two relatively transverse shafts, a worm on one of said 30 shafts, a worm-wheel member on the other shaft, meshed with said worm, a pair of drive elements for the worm shaft, coaxial with the worm shaft 35 at opposite ends of the worm, clutch connections between said elements and the worm shaft, a slide rod substantially parallel with the worm shaft, an arm on the worm-wheel shaft, means for actuating the slide rod from said arm, and means for 40 controlling said clutch connections by said slide rod.
